UNITED STATES PATENT OFFICE.

WILLIAM H. SAUVAGE, OF NEW YORK, N. Y., ASSIGNOR, BY MESNE ASSIGNMENTS,
TO GOULD COUPLER COMPANY, OF NEW YORK, N. Y.

SLACK ADJUSTER.

Application filed March 8, 1923. Serial No. 623,674.

To all whom it may concern:

Be it known that WILLIAM H. SAUVAGE, a citizen of the United States, residing at New York, in the county of New York and State of New York, has invented certain new and useful Improvements in Slack Adjusters, of which the following is a specification.

This invention relates to improvements in slack adjusters, and more particularly to automatic slack adjuster mechanism associated with the foundation brake rigging of railway vehicles. The invention will hereinafter be described with relation to its application to the brake cylinder usually located centrally beneath the car floor and to which the main levers are adapted to be connected.

One of the objects of the present invention is to provide a simple and practical slack adjuster mechanism adapted to be directly associated with the primary brake rigging of railway cars, which will be reliable and efficient in use and operation.

A further object is to provide an automatic slack adjuster, particularly applicable to foundation brake rigging, which will insure uniform piston travel at all times.

A further object is to provide a compact, durable and efficient slack adjuster mechanism of the above general character which may be inexpensively manufactured and assembled.

Other objects will be in part obvious and in part hereinafter pointed out in connection with the accompanying sheet of drawings showing one of various possible embodiments of the invention and in the several views of which similar parts are designated by corresponding reference characters.

In these drawings—

Figure 1 is a sectional plan view of the brake cylinder and associated parts;

Figure 2 is a detail sectional view of the slack adjuster mechanism; and

Figure 3 is a vertical view of the brake cylinder and associated parts.

Referring now to the drawings in detail, 5 designates the brake cylinder normally positioned centrally beneath the car floor. This cylinder is provided with an inlet pipe 6 for directing air or other fluid pressure means to the interior for co-action with a piston 8 provided with a piston rod 9 and a return spring 10. The piston rod 9 co-

operates with a live lever 11, as shown in 55 Figure 3. A dead lever 12 is pivotally connected at its upper end to a bifurcated portion 13 of an adjusting rod 14, which is supported in a casing 15 mounted on the car frame 16, and also from a pivotal connection 17 at one end of the cylinder 5. This adjusting rod is adapted to be automatically moved relatively towards the left as the slack is taken up due to wear of the parts of the brake rigging. It is normally held, 65 however, in the position shown in Figure 1 by means of a plurality of holding dogs 20 within a housing 21, said dogs being normally urged towards the left by a spiral spring 22 about the rod 14. Adjacent the 70 housing 21 is a second housing 23 provided with one or more dogs 24 as desired, only one being herein shown. This dog 24 is also urged relatively towards the left by means of a spring 25 as shown. The entire 75 housing 23 is movable towards and from the housing 21 on excess movement of the piston 8 by means of a bent rod 26 having a portion 27 within the cylinder 5 adapted to be engaged by the piston 8. When excess 80 travel takes place, the entire rod 26 is moved relatively towards the left, causing nuts 28 at its opposite end to engage with a support 30 associated with the housing 23 and move said housing towards the left against the 85 action of a spiral spring 31 surrounding the rod 14. The housings 21 and 23 have an inter-fitting locking engagement, as indicated at 32 for the purpose of preventing 90 relative turning movement of the two housings.

It is, of course, to be understood that the dogs 20 and 24 are of substantially the type shown in my numerous prior patents and comprise rectangular pieces of high grade 95 metal having holes therein through which the rod 14 is adapted to pass. The edges of the holes in the dogs are preferably hardened in order to insure a longer life and durable biting engagement with the rod. 100 These dogs will permit the rod to move relatively in one direction, that is, towards the right, but will not permit a movement in the opposite direction.

The apparatus herein shown and described operates substantially in the following manner: When air is admitted to the cylinder 5 through the port 6, the piston

8 is moved over its predetermined distance acting and reacting upon the live and dead cylinder levers 11 and 12, Figure 3, to cause the usual application of the brakes. If, 5 however, due to wear of the parts, brake shoes and wheels, excess travel takes place then the piston engages the end 27 of the rod 26 and moves that towards the left a distance exactly equal to the excess travel 10 of the piston. This, in turn, moves the housing 23 towards the left, compressing the spring 31 as shown in Figure 2. The dog at 24 during this operation is free to slide along the rod 14. When the brakes 15 are released the spring 31 will expand and the dog 24, having a new point of engagement with the rod 14, will cause the same to move towards the right a distance exactly equal to the excess travel, as shown, 20 for example, by the dotted line position of the rod 14. That is, the rod 14 is pulled towards the right freely through the dogs 20, which, in turn, take up a further biting or locking engagement with the rod 14. 25 This action is repeated from time to time as wear takes place until the bifurcated connection 13 moves nearly to the end of its path of travel in the pivoted arm or support 15, at which time it is necessary to 30 replace the worn parts, brake shoes, etc., and re-adjust the mechanism. In order to do this the dogs 20 and 24 are moved in any desired manner to a position at right angles to the axis of the rod 14 whereupon 35 this rod 14 may be restored to its normal position, as shown in Figure 1.

In order to permit ease of assembly, the support 15 is provided with a screw plug 33 for inserting the pivot pin 34 in the 40 top of the dead lever 12. The head of this pin is then locked in place by replacing the plug and travels in suitable grooves 35. The cylinder may also be provided with a leak groove 36 to allow the escape of any 45 air that may slowly leak into the cylinder, but is not of sufficient size to interfere with the normal application of the brakes.

It will thus be seen that the present invention provides a simple and practical 50 slack adjuster mechanism which will be reliable and efficient in use and operation. The parts may be inexpensively manufactured and assembled and applied to brake rigging now in general use without material modification or alteration of the lever mechanism.

Without further analysis, the foregoing 60 will so fully reveal the gist of this invention that others can, by applying current knowledge, readily adapt it for various applications without omitting certain features that from the standpoint of the prior art fairly constitute essential characteristics of the generic or specific aspects of this invention 65 and, therefore, such adaptations should and

are intended to be comprehended within the meaning and range of equivalency of the following claims.

I claim:

1. In an apparatus of the character described, in combination, a cylinder having a piston adapted to be connected to a live lever, a dead lever, a movable support for said dead lever comprising a rod, temporary take-up and holding means engaging said rod, adapted to be actuated on excess piston travel, means for moving said rod on excess travel to a newly adjusted position, said last named means including a member adapted to be engaged by said piston on excess travel thereof and means for holding said rod in said newly adjusted position. 70

2. In a slack adjuster for foundation brake rigging, in combination, a cylinder having a piston adapted to be connected with a live lever, an adjusting rod adapted to support a dead lever, permanent and temporary take up and holding means movable relatively towards and from each other during excess travel of the piston and release of the brakes and positioned in housings therefor, said take-up means each comprising a dog adapted to have a gripping engagement with the adjusting rod, and spring means between said housing acting upon the temporary take-up mechanism and reacting against the permanent take-up mechanism. 80

3. In a slack adjuster for foundation brake rigging, in combination, a cylinder having a piston, an adjusting rod, a temporary take-up mechanism coacting with said adjusting rod, means connected with said temporary take-up mechanism adapted to be actuated on excess piston travel, a permanent take-up mechanism, a spring between the permanent and temporary take-up mechanisms adapted to be compressed on excess travel and to expand on release of the brakes for permanently taking up the slack in the 90 100 brake rigging. 110

4. In a slack adjuster for foundation brake rigging, in combination, a cylinder having a piston, a member adapted to be engaged by said piston on excess travel thereof, a temporary take-up mechanism moved by said member on excess travel, a permanent take-up mechanism, an adjusting rod passing through the permanent and temporary take-up mechanisms, said mechanism each comprising a housing having a holding dog therein, and means for preventing relative turning of said housing. 115

5. In a slack adjuster for foundation brake rigging, in combination, an adjusting rod, a support for said rod including a housing, permanent take-up and holding dogs within said housing engaging said rod, a temporary take-up housing having a dog 120 125 130 engaging said rod, spring means between

said housing adapted to be compressed on excess travel and expand on release of the brakes to permanently take-up the slack.

6. In a slack adjuster for foundation brake rigging, in combination, an adjusting rod, a support for said rod including a housing, permanent take-up and holding dogs within said housing engaging said rod, a temporary take-up housing having a dog engaging said rod, spring means between said housing adapted to be compressed on excess travel and expand on release of the brakes to permanently take up the slack, and means for causing relative longitudinal movement of said housing on excess piston travel.

7. In a slack adjuster for foundation brake rigging, in combination, an adjusting rod, a support for said rod including a housing, permanent take-up and holding dogs within said housing engaging said rod, a temporary take-up housing having a dog engaging said rod, spring means between said housings adapted to be compressed on excess travel and expand on release of the brakes to permanently take up the slack, and means for causing relative longitudinal movement of said housing on excess piston travel, said means including a rod connected with the temporary take-up mechanism and having a reverse bend entering the cylinder and adapted to be engaged by the piston on excess travel.

8. In a slack adjuster for foundation brake rigging, in combination, an adjusting rod, a support for said rod including a housing, permanent take-up and holding dogs within said housing engaging said rod, a temporary take-up housing having a dog engaging said rod, and spring means be-

tween said housings adapted to be compressed on excess travel.

9. In a slack adjuster for foundation brake rigging, in combination, an adjusting rod, a support for said rod including a housing, permanent take-up and holding dogs within said housing engaging said rod, a temporary take-up housing having a dog engaging said rod, spring means between said housings adapted to be compressed on excess travel, and means preventing relative turning movement of the two housings.

10. In a slack adjuster for foundation brake rigging, in combination, an adjusting rod, a support for said rod including a housing, permanent take-up and holding dogs within said housing engaging said rod, a temporary take-up housing having a dog engaging said rod, spring means between said housing adapted to be compressed on excess travel, a lever, a pivot pin adapted to provide a pivotal connection between said lever and said rod and a guide for the pivot pin.

11. In a slack adjuster for foundation brake rigging, in combination, an adjusting rod, a support for said rod including a housing, permanent take-up and holding dogs within said housing engaging said rod, a temporary take-up housing having a dog engaging said rod, spring means between said housing adapted to be compressed on excess travel, a lever, a pivot pin adapted to provide a pivotal connection between said lever and said rod a guide for the pivot pin, and means for locking said pin in said guide.

In testimony whereof I affix my signature.

WILLIAM H. SAUVAGE.
